Inventor:
Edward Herst,
by Charles J. Harvey
his Atty.

UNITED STATES PATENT OFFICE.

EDWARD HERST, OF CHICAGO, ILLINOIS, ASSIGNOR TO PEERLESS LIGHT COMPANY, OF CHICAGO, ILLINOIS, A CORPORATION OF MAINE.

ELECTRIC-CANDLE SOCKET.

Application filed April 1, 1927. Serial No. 180,160.

This invention relates to electric candle sockets and its principal object is to provide an electric candle socket with improved clamping means for the adjustable supporting arms thereof whereby the device may be more readily lengthened and shortened to suit the individual taste. One object of this invention is to provide a candle socket having an adjustable yoke like supporting member, with a single screw for clamping together the two pieces of each arm of the supporting member. With these and other objects and advantages in view, this invention consists in the several novel features of construction, arrangement and combination of parts hereinafter fully set forth and claimed.

The invention is clearly illustrated in the drawing accompanying this invention, in which:

Fig. 1 is a front elevation of an electric candle socket embodying a simple form of the present invention; Fig. 2 is a side elevation thereof and Fig. 3 is a detail horizontal section taken on the line 3-3 of Fig. 1 and showing the device upon an enlarged scale.

Referring to said drawing, the electric candle socket comprises the usual screw shell 5 for the reception of an electric light bulb, a paper shell or other wall 6 surrounding the screw shell, and a supporting member 7 secured to the screw shell in any desirable manner. The screw shell has the usual electric connections for the electric conductor cords as is well understood.

The supporting member 7 comprises a pair of spaced arms 8, fastened to the screw shell and two spaced companion arms 9, which are adjustably mounted on the arms 8 and are formed up from a central, internally threaded nipple portion 10 thus providing a yoke shaped member, as is common and well understood. The threaded nipple portion 10 is adapted to be screwed upon the threaded member of the bracket arm or other electric fixture upon which the candle socket is to be used. All of the arms 8, 9 are channel shaped as shown, and the arms 9 fit between the flanges of the arms 8 and have a sliding connection therewith whereby the yoke shaped member may be adjusted lengthwise of the arms 8 to increase or decrease the length of the supporting member.

The arms 8 and arms 9 of the supporting

member are secured together by a single screw 11, which extends from one side to the other of the supporting member and passes through a sleeve or other strut 12 that extends between the opposing faces of the inner arms 8 and spaces them apart. The head of the screw bears against the outer face of one of the outer arms 9 of the yoke member and is threaded in an internally threaded aperture 13 formed in the other outer arm 9 of the yoke member. Lengthwise extending slots 14 are formed in the arms 8 whereby the two sections of the supporting member may be adjusted relative to each other to increase or decrease the length of the article. For supporting the paper shell 6, the arms 8 may be struck up to form tongues 15 that are bent laterally of the supporting member and engage with the lower edge of the paper shell.

It will be observed that only one screw is employed for connecting together the two arms 8 with the two arms 9 of the yoke shaped member and that with the interposed strut 12 the two pair of arms are held in spaced relation, and each two companion arms 8, 9 are frictionally held together when the screw 11 is screwed up tightly. The device is extremely simple and is easy to assemble and to adjust and when the single screw is tightened up, both sides of the supporting member are rigidly connected so that there is no danger of one side slipping down and throwing the article out of alignment.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. An electric candle socket, comprising a screw shell, a shell support for said screw shell comprising a pair of parallel shell supporting arms, parallel with, overlapping and secured to the screw shell, a yoke shaped supporting member having a pair of arms adjustably mounted on the first mentioned pair of arms, one of said pair of arms being slotted longitudinally, and the other pair having oppositely disposed screw holes, a

single screw extending through the screw holes and slots of all of the arms and having a head bearing against the outer face of one of the arms and threadedly connected with the other outer arm and a strut surrounding the screw and bearing against the inner faces of the inner arms.

2. An electric candle socket comprising a screw shell, a shell support composed of a pair of channel shaped, longitudinally slotted arms secured to and extending downward from said screw shell, a yoke shaped member having a pair of channel shaped arms, parallel with, fitting and slidably guided on the first mentioned pair of arms, said last mentioned arms having oppositely disposed screw holes, a single screw extending through the screw holes and slots of all of said arms with its head bearing against an outer one and threaded in an opposite outer one, and a strut surrounding said sin-

gle screw and confined between the inner arms.

3. An electric candle socket comprising a screw shell, a shell support for said screw shell comprising a pair of parallel shell supporting arms secured to the screw shell, a yoke shaped supporting member having a pair of arms, parallel, and interfitting with and adjustably mounted on the first mentioned pair of arms, one of said pair of arms being slotted longitudinally, and the other pair of said arms having oppositely disposed screw holes, a single screw extending through the screw holes and slots of all of the arms and having a head bearing against the outer face of one of the outer arms and threadedly connected with the other outer arm and a sleeve surrounding the screw and bearing against the inner faces of the inner arms.

EDWARD HERST.
